UNITED STATES PATENT OFFICE.

HOWARD F. GURNEY, OF JERSEY CITY, NEW JERSEY.

ELECTRIC ELEVATOR.

No. 851,934.

Specification of Letters Patent.

Patented April 30, 1907.

Application filed April 30, 1906. Serial No. 314,398.

To all whom it may concern:

Be it known that I, HOWARD F. GURNEY, a citizen of the United States, and a resident of Jersey City, in the county of Hudson and State of New Jersey, United States of America, have invented certain new and useful Improvements in Electric Elevators, of which the following is a specification.

My invention relates to an electric elevator and its object is to simplify and improve upon apparatus of this kind, and to provide certain means for the safe and efficient operation of electric elevators.

I will describe my invention in the following specification and point out the novel features thereof in claims.

Referring to the drawings, Figure 1 is a side elevation of an electric elevator constructed according to my invention. Fig. 2 is an end elevation of the apparatus shown in Fig. 1 with the motor removed and with certain parts shown in section. Fig. 3 is an enlarged end elevation of the brake and its connected parts. Fig. 4 is a detail of an automatic stop-motion switch. Fig. 5 is a detail of a part of the controller. Fig. 6 is a small diagrammatic view of an elevator hoisting apparatus built according to my invention with a car connected thereto.

Like characters of reference designate corresponding parts in all of the figures.

10 designates the base upon which the various parts of the hoisting mechanism are mounted.

11 is a casing mounted upon the base 10 and arranged to support the various parts of the apparatus.

12 is an electric motor which is mounted upon the base 10 and the casing 11, and the shaft 13 of which is connected to a winding drum 14 through suitable gearing within the casing 11.

15 designates the shaft of the winding drum 14.

16 designates brackets which extend above the casing 11 and which are adapted to support the shaft 17 upon which a traveling sheave 18 is mounted.

20 is a threaded shaft which is supported upon the casing 11 by means of journal-boxes 21. A gear 22 is loosely supported upon the threaded shaft 20. The inner portion of this gear 22 is provided with screw-threads which mesh with the screw-threads of shaft 20. Its upper portion is provided

with gear-teeth which mesh with a gear 23 which is rigidly mounted upon the shaft 15 of the winding drum and arranged to move with the drum.

24 and 25 are adjustable collars, the inner portions of which may be threaded and arranged to be placed upon the threaded shaft 20 and held in place upon said shaft by set-screws 24A and 25A. These collars are provided with projecting lugs 24B and 25B which are adapted to engage, respectively, with similar lugs 22A and 22B on the gear 22.

At one end of the threaded shaft 20 a cam member 26 is attached. One portion of this cam member 26 may be provided with a sprocket-wheel 26A. A sprocket-chain 26B is arranged to pass over this sprocket-wheel 26A and its ends are connected to a weight 26C. Another cam member 27 is also rigidly attached to the threaded shaft 20.

30 designates a stop-motion switch, the various parts of which are mounted upon a base 31 of slate or other suitable insulating material which is rigidly attached to the casing 11 by brackets 32 which connect this base 31 to the right-hand journal-box 21. The stop-motion switch 30 is shown somewhat in detail in Fig. 4. It comprises a contact lever 33 which is pivoted at 34, and which carries at one end a contact 35. This contact 35 is normally held against a stationary contact 36 which is mounted upon the base 31, by a spring 37. The contact lever 33 may also carry an antifriction roller 38. The stop-motion switch also comprises another contact-lever 39 which is similar to contact lever 33 and which has similar parts to those just described. The cam member 26 is placed between the antifriction roller 38, on the contact lever 33, and a similar antifriction roller on the contact 39. The cam member carries an enlarged portion 26D which is arranged to be moved against the antifriction roller 38 and to thereby cause the contact lever 33 to be moved against the action of the spring 37 so that it raises the contact 35 away from contact 36. The portion 26D is also arranged to be moved against the antifriction roller on contact lever 39 and to cause the latter to move its movable contact away from the stationary contact against which it normally rests.

40 designates a brake which comprises arms 41 and 42 which are pivoted at 41A and 42A to the base 10 and which are arranged to

coact with a brake-pulley 43 which may be mounted upon the motor shaft 13. This brake-pulley 43 may, if desired, be made in the form of a coupling and arranged to connect the end of the motor shaft 13 to another shaft 13A in alinement with the motor shaft and connected to the gearing within casing 11. The pivoted arms 41 and 42 are arranged to be actuated by a weighted lever 44 which is pivoted at 44A to a bracket 19 which is connected to a part of the casing 11. 45 is a weight upon this lever 44, the position of which may be regulated and which may be held in place upon the lever 44 by a set-screw 45A. An antifriction roller 44B may be mounted upon the pivoted arm 44. This pivoted arm 44 is provided at one end with a projection 46 which is connected to the pivoted arm 42 by a link 46A. It is also provided with another projection 47 which is connected to the pivoted arm 41 by a link 47A, the length of which link may be adjusted by means of a screw 47B. The cam member 27 is arranged to be directly above the antifriction roller 44B upon the lever 44. This cam member 27 is arranged to have two cam surfaces 27A and 27B at different distances from the center of threaded shaft 20, and these cam surfaces are arranged to engage with antifriction roller 44B and to actuate the pivoted lever 44 in a manner which will be pointed out fully hereinafter.

50 designates an electric controller, the various parts of which are mounted upon a base 51 of slate or other suitable insulating material. This base 51 is mounted upon the casing 11 and supported by a bracket 16A which projects from one of the brackets 16. This controller 50 comprises a starting switch 60, a reversing switch 70, and an automatic rheostat 80, all of which are arranged to be controlled and operated by an electromagnet 90. This electromagnet is of the solenoid type and comprises a frame 91 which is mounted upon the casing 11. It also comprises a spool or winding 92 and a core 93. The lower end of this core 93 is connected by means of an adjustable rod 94 to the pivoted weighted lever 44 at 94A. The upper end of the core 93 is connected by a rod 95 to the piston 96 of a retarding device or air-cushion which comprises the piston 96 and an inclosed cylinder 96A in which the piston 96 moves. The rod 95 is continued above this air-cushion to a rod 61 of the starting switch 60 and is attached thereto, and two movable contact-plates 62 and 63 are connected to but insulated from this rod 61 and are arranged to be moved up against stationary contacts 64, 65 and 66, 67, respectively, as shown in Fig. 2, or to be moved down away from these stationary contacts, in which case the contact-plate 63 will rest upon stationary contacts 68 and 69.

65 The reversing switch 70 comprises a rod 71

in alinement with the rod 61 and which carries contact-plates 72 and 73 which are arranged to be moved up against stationary contacts 74, 75 and 76, 77, respectively, or down against stationary contacts 78, 79 and 78A, 79A, respectively. This reversing switch 70 is arranged to be held in either of its operative positions in a manner which will be described later.

100 designates a magnet which is arranged to control the positions and the operation of the reversing switch 70. This is shown somewhat in detail in Fig. 5. It comprises a magnet-frame 101, a winding 102 and a core 103. This core 103 is connected by a rod 104 to a movable piece 105, which is arranged to carry a pin 106 which is in a slot 71B in a pendant 71A which is pivoted to the lower end of reversing switch rod 71. The movable piece 105 is also arranged to actuate a latch 107 which is pressed outward by a spring 108 and arranged to take into a projection 71C on the lower end of the reversing switch rod 71. The movable piece 105 is further arranged to actuate a movable contact 110 which is arranged to bridge and to connect stationary contacts 111 and 112, or stationary contacts 113 and 114 which are shown in Figs. 1 and 2.

An arm 120 is pivoted at 121 to stationary brackets on the top of the air-cylinder 96A. One end of this arm is directly below the rod 51 of the starting switch 60 and the other end of the arm is associated with a rod 81 of the automatic rheostat 80. The lower end of this rod 81 is connected to the piston of a dash-pot 82 and its upper end carries brushes 83, 84 and 85 which are connected to the rod 81. These brushes are arranged to be moved over stationary contacts 86, 86 to which resistances 87, 87 are connected. A plate 85A is connected to but insulated from the upper brush 85 on the rod 81 and is arranged to connect two stationary contacts 88 and 89 when it is at the upper end of its travel.

When the starting switch 60 is in its raised position the rod 81 of the automatic rheostat is allowed to move under the action of gravity at a predetermined rate of speed governed by the dash-pot 82 down across the stationary contacts 86, 86, and the pivoted arm 120 will move with it. The rod 61 of the starting switch, when it is in its raised position, will be moved above the travel of the right-hand portion of pivoted arm 120.

130 designates an elevator-car which may be connected to the winding-drum 14 by means of ropes or cables 131 which pass up over a sheave or sheaves 132 above the upper limit of the travel of the car, and thence down to the drum 14 to which they are attached. A manually operated switch 133 may be placed in this car and electrically connected to the controller 50 and arranged so that an operator in the car may control the starting,

stopping and reversing of the motor 12. A counterweight 134 may be connected to the other side of the winding-drum 14 by means of ropes or cables 135 which pass over a stationary sheave 136 and over a traveling sheave 18 on the hoisting mechanism and to the drum 14 to which they are attached.

I have pointed out the various parts of my apparatus and will now describe their operation.

Whenever an operator moves the switch 133 to start the elevator, the magnet 90 of the controller 50 is connected by suitable electrical circuits to a source of electrical supply through the car switch 133. The winding 92 will then be energized and will raise its core 93. This will cause the weighted pivoted lever 44 to be raised and to release the brake, and through its various connections to release the arms 41 and 42 from the brake-pulley 43. It will at the same time raise contacts 62 and 63 of the starting switch against stationary contacts 64, 65 and 66, 67, and will thereby connect circuits to the motor which will cause the latter to start. The rod 61 of the starting switch will thereby be raised up above the right-hand end of the pivoted arm 120 and the rod 80 of the automatic rheostat will allow its contacts to move downward over stationary contacts 86, 88 under the control of dash-pot 82 and will thereby cause the resistances 87, 88 to be cut out of the motor circuit. If the arm 71 of the reversing switch is held in its upper position, by latch 107 engaging with projection 71C on reversing switch rod 71, the movement of the starting switch will have no effect upon the reversing switch. The contacts 111 and 112 which magnet 100 controls are then connected by contact 110 and the circuits are in proper connection for operating the motor and its connected car in one direction.

The operator may stop the motor and car by bringing the car-switch back to its central position, in which case the magnet 90 will be deenergized and will allow its core 93 to drop. This will cause contacts 62 and 63 to be moved away from their stationary contacts because the rod 61 is connected to core 93 by rod 95, and through the connection 94 will cause pivoted weighted lever 44 to apply the brake to brake-pulley 43. It may be seen that the pivoted arms 41 and 42 which are arranged to engage with the brake-pulley 43 are through their various connections brought together by the action of gravity on the lever 44. The amount of pressure of these arms on the brake-pulley may be regulated by shifting the position of weight 45 which, together with the core 93 and its connected parts, causes the arms 41 and 42 to be brought against the brake-pulley 43. The first movement of rod 61 will open the motor circuits; a further movement will cause the right-hand end of pivoted arm 120 to be de-

pressed and to raise the arm 81 of the automatic rheostat up so that its brushes 83, 84 and 85 will again move over stationary contacts 86, 86 and thereby include resistances 87, 87 in the motor circuit, and to bridge stationary contacts 88 and 89.

The starting and stopping of the motor, as above described, may be repeated indefinitely. If, however, the operator desires to start the motor and the car in the opposite direction he will move the car-switch 133 in the opposite direction. In this case the circuits which are completed will pass through magnet 100 and cause the latter to move the latch 107 back away from projection 71C, and at the same time will move pendant 71A back out of the path of movement of rod 61 of the starting switch. The contacts 72 and 73 of the reversing switch will then be allowed to drop down on the contacts 78, 79 and 78A, 79A and this will cause the circuits to the motor to be made in the opposite direction when the starting switch is closed. The operator may stop the motor in the manner previously described and may repeat this operation indefinitely as the circuit from the car-switch to the magnet 90 passes through magnet 100. Whenever the operator moves the switch in this second direction the magnet 100 will move the pendant 71A away from the path of travel of rod 61 so that the reversing switch contacts 72 and 73 will remain in their lower position. As soon, however, as the operator moves the car-switch 133 to the first position described, the magnet 90 will be energized but the magnet 100 will not be energized, and in this case, when the rod 61 of the starting switch is raised, it will engage with pendant 71A and raise it and rod 71 of the reversing switch up until the latter is engaged and supported by the latch 107. Thus it may be seen that the parts are so arranged that the reversing switch is held in either one of its operative positions as long as the operator desires to start the car in one direction, and that the position of the reversing switch does not change except when it is desired to change the direction of the car's travel.

The electrical circuits above mentioned are not shown in the drawings herein because they are fully shown and described and are made the subject-matter of another application Serial Number 314,397, filed April 30, 1906.

The air-cushioning device 96 and 96A is provided for the purpose of preventing slamming of the parts which are operated by the magnet 90. It is preferably arranged to be double-acting so that when the magnet 90 is energized and raises its core the upper portion of the movement of the core and its connected parts will be retarded; and similarly, when the magnet 90 is deenergized the lower part of the movement of the core 93 and its

connected parts will be retarded. Therefore, the end of both the upward and downward movement of the parts will be gradual and will thus be free from noise and jar.

I will now describe the operation of the means which I have invented for bringing the car to rest automatically when it has reached the limit of its travel. I have shown that the gear 23 moves with the winding drum 14. This gear 23 causes the gear 22 which is in mesh with it to be rotated on the threaded shaft 20 and thereby causes the gear 22 to have a longitudinal movement to one side or the other, according to the direction of rotation of the drum 14. The adjustable collars 24 and 25 are so set that their projections 24B or 25B engage with the projections 22A or 22B whenever the car approaches one end or the other of its travel. Let us for example say that the car is approaching the downward limit of its travel and that the gear 22 is moved to the left, in which case the projection 22A engages with projection 24B on the adjustable collar 24; the two parts will then be locked together and the gear 22 will thereby cause the threaded shaft 20 to turn in an anti-clockwise direction with it. This will cause the cam member 26 and 27 to be rotated. The first effect of this rotation of the cam members will be that of the projecting portion 26B of cam member 26 engaging with the anti-friction roller 38 on contact lever 33 to move contact 35 away from contact 36. These contacts are electrically connected with the circuit of the car-switch 133 and will break the same circuit that the operator would break if he would move the car-switch back to its off or stop position. In other words, it would break the circuit through magnet winding 92 of magnet 90 and cause the motor circuit to be broken and the brake to be applied in the manner already described. A further rotation of threaded shaft 20 will close the cam-face 27A of cam member 27 to engage with antifriction roller 44B on the pivoted weighted lever 44 and will thereby pull the core 93 and its connected parts downward and thereby mechanically separate movable contacts 62 and 63 from stationary contacts 64, 65 and 66, 67, if, for any reason, they had not dropped away from them when the magnet 90 was deenergized. A still further rotation of threaded shaft 20 will cause cam-face 27B of the cam member 27 to engage with the antifriction roller 44B and to thereby force the lever 44 downward and thereby force the brake-arms 41 and 42 onto brake-pulley 43 with great power. It may be seen from the above that the automatic stop-motion which I have invented has three distinct steps, the first of which breaks the operating circuit, the second of which mechanically opens the motor

circuit, and the third of which forces on the 65 brake-arms under great power.

Whenever the threaded shaft 20 is moved, as above described, the sprocket-chain 26B will be moved by the sprocket-wheel 26A and will cause the weight 26C to be raised. 70

I have described the method in which the movement of this shaft will bring the elevator mechanism to rest. If, now, the mechanism is operated in the opposite direction, the projection 22A on the gear 22 will be moved back away from projection 24B on the adjustable collar 24. The weight 26C will then cause the threaded shaft 20 and its connected parts to be returned again to their original positions. 75

When the car reaches the other end of its travel the projection 22B on the gear 22 will engage with the projection 25B and the adjustable collar 25 and will cause the various parts previously described to be operated in a similar manner to bring the hoisting mechanism and the car to rest. 85

What I claim is.—

1. In an electric elevator, the combination of a hoisting mechanism, a motor, a starting switch, a reversing switch and an automatic rheostat, and an electromagnet arranged to control the starting switch, the reversing switch and the automatic rheostat. 90

2. In an electric elevator, the combination of a hoisting mechanism, a motor, a starting switch, a reversing switch, an automatic rheostat and a brake, and an electromagnet arranged to control the starting switch, the reversing switch, the automatic rheostat and 100 the brake. 95

3. In an electric elevator, the combination of a hoisting mechanism, a motor, a reversing switch therefor having two operative positions and arranged to be held in either of said operative positions, an electrically actuated starting switch for said motor, said switch being entirely independent of the reversing switch, and means for mechanically connecting the reversing switch to move with 105 the starting switch. 110

4. In an electric elevator, the combination of a hoisting mechanism, a motor, a brake, a reversing switch for the motor having two operative positions and arranged to be held 115 in either of said operative positions, a starting switch, an electromagnet arranged to actuate the brake and the starting switch independently of the reversing switch, and means for mechanically connecting the reversing switch to be actuated by the electromagnet with the brake and the starting switch. 120

5. In an electric elevator, the combination of a hoisting mechanism, a motor, a reversing switch therefor having two operative positions and arranged to be held in either of said operative positions, a starting switch, 125

an electromagnet arranged to actuate the starting switch independently of the reversing switch, an air-cushion arranged to control the movement of the electromagnet, and means for mechanically connecting the reversing switch to be actuated by the electromagnet with the starting switch.

6. In an electric elevator, the combination of a hoisting mechanism, a motor, a brake, an automatic rheostat for the motor, a reversing switch having two operative positions and arranged to be held in either of said operative positions, a starting switch, an electromagnet arranged to actuate the brake and the starting switch independently of the reversing switch and to control the automatic rheostat, and means for mechanically connecting the reversing switch to be moved by the electromagnet with the brake and the starting switch.

7. In an electric elevator, the combination of a hoisting mechanism, a motor, a brake, an automatic rheostat for the motor, a dashpot for controlling the action of the rheostat, a reversing switch for the motor having two operative positions and arranged to be held in either of said operative positions, a starting switch, an electromagnet arranged, when energized, to actuate the starting switch and the brake independently of the reversing switch and to control the automatic rheostat, and means for mechanically connecting the reversing switch to be moved by the electromagnet with the starting switch and the brake.

8. In an electric elevator, the combination of a hoisting mechanism, a motor, a reversing switch therefor, said reversing switch having a movable member arranged to be held in one operative position by gravity and in a second operative position by a latch, an electrically actuated starting switch for the motor arranged to be actuated independently of the reversing switch, means for mechanically connecting the reversing switch to be moved by the starting switch into its second operative position, and an electromagnet for controlling the connecting means and for releasing the latch to allow the reversing switch to move back into its first operative position.

9. In an electric elevator, the combination of a hoisting mechanism, a motor, a starting switch therefor, a brake, an electromagnet arranged to control the starting switch and the brake, and an automatic stop-motion actuated by the motor and arranged to successively de-energize the electromagnet, to force open the starting switch, and to force on the brake.

10. In an electric elevator, the combination of a hoisting mechanism, a motor, an electrically actuated starting switch therefor, an electrically actuated brake, an electromagnet arranged to control the starting switch and the brake, a switch arranged to

control said magnet, and an automatic stop-motion actuated by the movement of the motor and arranged to successively open said magnet-controlling switch, to mechanically force open the starting switch and to mechanically force on the brake. 7c

11. In an electric elevator, the combination of a hoisting mechanism, a motor, a starting switch, a reversing switch, an automatic rheostat, an electromagnet arranged to control the starting switch, the brake and the automatic rheostat, and an automatic stop-motion actuated by the movement of the motor and arranged to successively de-energize the electromagnet to force open the starting switch and to force on the brake. 75

12. In an electric elevator, the combination of a hoisting mechanism, a motor, a brake, a reversing switch for the motor having two operative positions and arranged to be held in either of said operative positions, a starting switch, an electromagnet arranged to actuate the starting switch independently of the reversing switch, an air-cushion arranged to control the movement of the electromagnet, means for mechanically connecting the reversing switch to be actuated by the electromagnet with the starting switch, and an automatic stop-motion actuated by the movement of the motor and arranged to successively de-energize the electromagnet to force open the starting switch and to force on the brake. 85

13. In an electric elevator, the combination of a hoisting mechanism, a motor, a brake, a reversing switch for the motor, said reversing switch having a movable member arranged to be held in one operative position by gravity and in a second operative position by a latch, an electrically actuated starting switch for the motor arranged to be actuated independently of the reversing switch, an electromagnet for actuating the starting switch and the brake, means for mechanically connecting the reversing switch to be moved by the starting switch into its second operative position, and a second electromagnet for controlling the connecting means and for releasing the latch to allow the reversing switch to move back to its first operative position, and an automatic stop-motion actuated by the movement of the motor and arranged to successively de-energize both electromagnets to mechanically force open the starting switch and to mechanically force on the brake. 105

14. In an electric elevator, the combination of a winding-drum, a motor, intermediate mechanism connecting the winding-drum and the motor, a brake, a switch arranged to control the brake, a starting switch for the motor, an electromagnet arranged to control the starting switch and the brake, a threaded shaft connected to run with the winding-drum, a traveling nut on said threaded shaft, 125

adjustable collars associated with said traveling nut, and a cam arranged to be actuated by said traveling nut and adjustable collars and arranged to successively open the magnet-controlling switch to mechanically force open the starting switch and to mechanically force on the brake.

In testimony whereof I have signed my name to this specification in the presence of two subscribing witnesses.

HOWARD F. GURNEY.
